CONCRETE BLOCK MOLDING MACHINE

Vernon H. Michael, Loveland, Ohio

Application February 10, 1950, Serial No. 143,520

5 Claims. (Cl. 25—41)

1

This invention relates to concrete block-forming machines, and more particularly to means for automatically feeding material to the concrete block machine and for automatically stripping the molded blocks from the machine.

A main object of the invention is to provide a novel and improved automatic feeding and stripping attachment for a concrete block machine, said attachment being relatively simple in construction, being reliable in operation, and providing a great saving in time and labor in the forming of concrete building blocks by the use of a block-molding machine.

A further object of the invention is to provide a novel and improved automatic feeding and stripping attachment for a concrete block machine, said attachment being inexpensive to manufacture, being adaptable for a wide range of different types of block machines, being rugged in construction, and providing alternate cycles wherein material is first fed to the concrete block machine to be molded, and wherein the molded blocks are subsequently stripped from the molding machine in timed sequence with respect to the operation of the material-feeding portion of the attachment.

A still further object of the invention is to provide an improved feeding and stripping attachment for a block-molding machine, said attachment being relatively compact in size, involving only a few parts, being easy to maintain and to adjust, requiring a relatively small power unit, and greatly reducing the cost of manufacture of molded concrete blocks.

Further objects and advantages of the invention will become apparent from the following description and claims, and from the accompanying drawings, wherein:

Figure 1 is a side elevational view of an attachment according to the present invention arranged for use with a conventional concrete block-molding machine;

Figure 2 is a horizontal cross-sectional view taken on line 2—2 of Figure 1;

Figure 3 is an end elevational view of the attachment shown in Figure 1;

Figure 4 is a cross-sectional detail view taken on line 4—4 of Figure 2;

Figure 5 is a top plan detail view of the gravity-operated tripper mechanism employed in the attachment of Figure 1;

Figure 6 is a side elevational view of the tripper mechanism of Figure 5;

Figure 7 is an end elevational view of the tripper mechanism of Figure 5;

2

Figure 8 is an enlarged perspective detail view of the slotted connecting rod employed to drive the main feed carriage propelling arm of the attachment of Figure 1.

Referring to the drawings, 11 designates a base plate on which is mounted a conventional block-molding machine 12. The block-molding machine is provided with a block-stripping mechanism operated by a pivoted arm 13, which functions in a well known manner to eject a molded block from the machine responsive to counterclockwise rotation of the arm 13 from the position shown in Figure 1.

Secured to the base 11 are vertical end supports 14 connected by suitable cross-braces to define a frame at the left end of the apparatus, as viewed in Figure 1. Secured to the base 11 are vertical intermediate supports 15 connected by suitable cross-braces and connected by longitudinal, horizontal angle bars 16 to the end supports 14, the horizontal flanges of the angle bars being inwardly directed, as shown at 17, to define supporting tracks. The respective bars 16 are braced to the supports 15 by respective brace bars 18.

Designated at 19 is a stationary hopper secured in any suitable manner in overlying relation to the forward end of the receiving table 20 of the block machine 12. Designated at 21 is a sliding carriage provided with rollers 22 engaging the track flanges 17 and carrying a hopper 23 extending substantially from the plane of the discharge opening of hopper 19 to the top plane of the receiving table 20 and being received in an upwardly flared hopper member 24 slidably carried on said table. The feeder carriage 21 carries a horizontal valve plate 25 which covers the bottom of stationary hopper 19 when the carriage is moved to the left from the position shown in Figure 1 in transferring material to the mold cavities of the machine 12.

Secured to the right end of the base plate 11, as viewed in Figure 1, are vertical end supports 26, and secured to the top ends of supports 26 and to the supports 15 is a horizontal frame 27 on which are mounted the respective motors 28 and 29. The shaft of motor 28 is coupled by suitable pulleys and a belt 30 to a vibrator 31 carried by the receiving table 20. Motor 28 is connected to a suitable power source through a normally open control switch 32 secured beneath the frame 27. Switch 32 has an operating shaft 33 carrying a depending arm 34 provided at its end with a contact roller 35, as shown in Figure 4.

Secured to base 11 inwardly of the intermediate

vertical supports 15 is a block 36 to the side of which is pivoted an upwardly extending arm 37. The top end of arm 37 is connected by a link bar 38 to a depending flange 39 carried by the carriage 21.

Secured to base 11 below motor 29 is an upstanding support 40. Journaled in the upper portion of support 40 is a first transverse shaft 41 carrying respective small gears 42 and 43 and carrying a large pulley 44. Pulley 44 is coupled to a pulley 45 carried on the shaft of motor 29 by a belt 46. Mounted in the support 40 below shaft 41 is another shaft 47 on the end portions of which are journaled the respective large gears 48 and 49 meshing respectively with the small gears 42 and 43. Secured to gear 49 is an arm 50. Pivoted to the end of arm 50 is a connecting rod 51 formed with a longitudinal slot 52. The arm is hooked downwardly at its end, as shown at 53, the slot therein being similarly hooked downwardly, as shown at 54. Arm 37 carries a pin 55 which is slidably engaged in the slot in connecting rod 51. In the position shown in Figure 4, rod 51 is ineffective to deliver clockwise thrust to arm 37 since the pin 55 is in the straight portion of the slot 52. When the connecting rod 51 is lifted, the pin 55 may become engaged in the hooked slot portion 54, whereby clockwise thrust may be delivered to the arm 37 by said connecting rod responsive to the rotation of arm 50.

Pivoted to the intermediate portion of arm 37 at 57 is a link bar 56, and pivoted to bar 56 at 58 is a depending arm 59 carrying a laterally extending roller 60 at its lower end which underlies the connecting rod 51. Designated generally at 61 is a tripping mechanism carried on an upstanding bracket 62 secured to frame 27. As shown in Figure 3, the tripping mechanism comprises a lever 63 pivoted at 64 to the top end of bracket 62 for rocking movement. One end of lever 63 is connected by a chain 65 to the top end of arm 59.

Secured to gear 48 is an arm 66. Designated at 67 is a collar slidably mounted on the stripper arm 13. Designated at 72 is an arm pivoted at 73 to the adjacent support 15. A link bar 68 is pivoted at one end to the collar 67. Link bar 68 is upwardly angled at its other end, as shown at 74, and is pivotally connected at 75 to the end of arm 72. Link bar 68 is formed with an elongated slot 70 having an upwardly directed end portion 71 adjacent the angled bar portion 74. Designated at 76 is a connecting rod pivotally connected at 77 to the end of arm 68. Secured to the end of rod 76 is a block member 78 carrying a pin 79 which is slidably received in the slot 70. When the pin 79 is in the straight portion of the slot 70, no counterclockwise thrust, as viewed in Figure 1, can be transmitted by rod 76 to the stripper arm 13. When the block 78 is lifted, the pin 79 may become engaged in the upwardly directed slot portion 71, whereby counterclockwise thrust may be delivered to the stripper arm 13, as viewed in Figure 1, responsive to rotation of arm 66.

Designated at 81 is a lever pivoted at 81 to the support 15 adjacent the bar 68, said lever 80 is underlying the block 78. The end of lever 80 is connected by a chain 82 to the end of tripper lever 63 opposite to the connection of chain 65.

The top portion of bracket 62 carries opposing triangular stop flanges 83, 83 underlying the lever 63, as shown in Figure 6, and limiting the rocking movement of said lever. Secured to the ends of the lever 63 are parallel, opposing, horizontal arms 84 and 85, and secured to the ends of said arms is a track rod 86. Designated at 87 is a

weighted block having upstanding hanger brackets 88 to the ends of which are journaled grooved rollers 89, 89 engaged on the track rod 86, whereby the block 87 is movably suspended from the track rod. Rocking of the lever 63 clockwise, as viewed in Figure 6, causes the block 87 to move by gravity to the position of Figure 3, applying tension to chain 82. Conversely, rocking of the lever 63 counterclockwise causes the block 87 to move to the left in Figure 3, applying tension to the chain 65.

In order to rock the lever 63, it is necessary to move block 87 from one end of the track rod toward the other, past the dead center position 15 of the block with respect to said track rod. Referring to Figure 5, it will be seen that a first cable 90 is connected to one of the brackets 88 and that a second cable 91 is connected to the other bracket 88. Cable 90 extends around pulleys 92 and 93 on the lever 63 and over a pulley 94 on the brace bar 18 and is fastened to the stripper arm 13 at 95. Cable 91 extends around pulleys 96 and 97 on the lever 63 and is fastened to the top portion of arm 37 at 98. From Figure 25 it will be seen that counterclockwise movement of stripper arm 13 will produce tension in cable 90, causing block 87 to be moved toward the left, as viewed in Figure 5, overbalancing the lever as the block moves past dead center, and causing the lever to be rocked counterclockwise, as viewed in Figure 6. As above mentioned, this produces tension in chain 65, at the same time removing tension from chain 82. The tension applied to chain 65 causes roller 60 to lift slotted arm 51 to engage the slot portion 54 thereof with the pin 55. When tension is removed from chain 82, lever 80 is free to drop, and block 78 descends, allowing pin 79 to enter the straight portion of slot 70, terminating the thrust on stripper arm 13.

From Figure 4 it will be seen that clockwise movement of arm 37 produces tension in cable 91, causing the weight 87 to be shifted to the right in Figure 5, and causing the lever 63 to be rocked clockwise, as viewed in Figure 6, whereby tension is provided in chain 82 and tension is removed from chain 65.

In operation, gears 48 and 49 are driven continuously causing the arms 66 and 50 to be continuously rotated. Assume the parts to be in the position of Figure 1. In this position the mold has been filled by a previous feeding stroke of hopper 23 and is ready to be stripped. Chain 82 is in tension and lever 80, therefore, supports pin 79 in coupling position in slot portion 71 of arm 66. At the same time, pin 55 of arm 37 is in the straight portion of the slot 52 in arm 51. Arm 66 now rotates and drives stripper arm 13 counterclockwise, stripping the molded block from the machine 12. As this occurs, lever 63 is rocked by cable 90, releasing lever 80 and lifting arm 59 so that roller 60 exerts lifting force on connecting rod 51. At this point pin 55 is in an intermediate position in slot 52 so that connecting rod 51 cannot as yet drive the feeding arm 37. Continued rotation of crank arm 66 causes the pin 79 to return through the slot 70, restoring the tripper arm 13 to its starting position as the pin 79 engages the slot portion 71 and retracts arm 68. This completes the stripping cycle. At this point the connecting rod 51 has been moved to a position wherein said rod may be lifted to engage its slot portion 54 with the pin 55, the roller 60 exerting the required lifting force. Continued rotation of 70 crank arm 66 then produces clockwise thrust

on arm 37, moving the hopper 23 toward its discharge position over the mold cavities. Tension is produced in cable 91, causing the lever 63 to be rocked. This releases the tension on chain 65, releasing arm 59 and allowing the connecting rod 51 to descend so that said rod can transmit no further thrust to arm 37. As the arm 37 swings clockwise, as viewed in Figure 4, an extension 99 thereon (Figure 2) engages the switch roller 35 energizing the vibrator 31. At this point, the hopper 23 is over the mold cavities and discharges into said cavities. The chain 82 is also in a taut condition, but pin 79 is in an intermediate position in slot 70, so that the stripper arm 13 cannot as yet be actuated. As arm 59 continues its rotation, connecting rod 51 is retracted, returning arm 37 to its initial position, shown in Figure 1. Roller 35 is released, de-energizing the vibrator. As arm 68 returns to its original position, shown in Figure 1, pin 79 is lifted into slot portion 71, and the above-described cycle of operations is then repeated.

It is thus apparent that during one revolution of gear shaft 47 the feed hopper 23 is moved from beneath the supply hopper 19 to a position over the mold cavities, the material is discharged from said feed hopper into said cavities, the mold is vibrated, and the feed hopper 23 is returned to its original position beneath the supply hopper. During the next revolution of the gear shaft 47, the stripper arm 13 is rotated, causing the molded block to be ejected from the mold, and the stripper arm 13 is returned to its starting position. The movement of arm 37 toward feeding position of feed hopper 23 trips the lever 63, establishing tension in chain 82 for subsequently coupling connecting rod 76 to the stripper arm 13. The movement of stripper arm 13 toward block-stripping position again trips lever 63, establishing tension in chain 65 for subsequently coupling connecting rod 51 to the arm 37 for initiating the mold feeding cycle.

The switch operated by roller 35 may be connected in the energizing circuit of a suitable time relay having a first set of normally open contacts controlling the vibrator motor 28 and a second set of normally closed contacts in the energizing circuit of the main motor 29. The contacts of this time relay are arranged to close the energizing circuit of the vibrator motor responsive to engagement of roller 35 by extension 99, and at the same time to open the energizing circuit of main motor 29 for a definite period of time. Thus, when the vibrator motor is energized, the time relay stops the main motor 29 for said time period. This lengthens the time of operation of the vibrator, making for a much more solid block.

Although a specific embodiment of a mechanism for automatically feeding material to a concrete block machine and stripping the molded blocks from the machine has been disclosed in the foregoing description, it is to be understood that various modifications within the spirit of the invention may occur to those skilled in the art. Therefore, it is intended that no limitations be placed on the invention except as defined by the scope of the appended claims.

What is claimed is:

1. An apparatus of the character described comprising a support, a concrete block-molding machine mounted on said support, said machine having a top table provided with mold cavities and having a block-stripping mechanism, a stationary hopper carried on said support above

the table and offset from said mold cavities, guide rails carried on said support and extending between the bottom of said hopper and a position above said cavities, a carriage slidably mounted on said guide rails, a feed hopper carried by said carriage, said feed hopper being registrable in a first position of said carriage with the bottom of said stationary hopper and in a second position of said carriage with the mold cavities, a rotatable shaft mounted on said support, a crank member secured to said shaft, means releasably connecting the crank member to the carriage, and means releasing the connection between the crank member and the carriage responsive to operation of the block-stripping mechanism.

2. An apparatus of the character described comprising a block-molding machine having a block-stripping mechanism, a reciprocable feed hopper movable back and forth over said block-molding machine, a drive shaft, first reciprocable coupling means connecting said drive shaft to the feed hopper, second reciprocable coupling means connecting the drive shaft to the stripping mechanism, means for disconnecting the second coupling means responsive to forward feeding movement of the feed hopper, and means for disconnecting the first coupling means responsive to forward operating movement of the block-stripping mechanism.

3. An apparatus of the character described comprising a block-molding machine having a block-stripping mechanism, a reciprocable feed hopper movable back and forth over said block-molding machine, a drive shaft, a first reciprocable coupling means detachably connecting said drive shaft to the feed hopper, second reciprocable coupling means detachably connecting the drive shaft to the stripping mechanism, a tripping mechanism comprising a movable member, and respective means connecting said movable member to said feed hopper and to said stripping mechanism, said movable member being formed and arranged to disconnect the first coupling means in one position of the movable member and to disconnect the second coupling means in another position of the movable member.

4. An apparatus of the character described comprising a block molding machine having a reciprocable block stripping mechanism, a feed hopper positioned adjacent said block molding machine and mounted for movement from the position adjacent said block molding machine to a position over said block molding machine, a drive shaft, a first reciprocable coupling means connecting said drive shaft to said block stripping mechanism and responsive to completion of movement of said feed hopper to the position adjacent said block molding machine for effecting the reciprocation of said block stripping mechanism, and a second reciprocable coupling means connecting said drive shaft to said feed hopper and actuatable in response to movement of said feed hopper to the position over said block molding machine for maintaining said block stripping mechanism against reciprocation.

5. An apparatus of the character described comprising a block molding machine having a reciprocable block stripping mechanism, a feed hopper positioned adjacent said machine and mounted for movement from the position adjacent said block molding machine to a position over said block molding machine, a drive shaft, a first reciprocable coupling means connecting said drive shaft to said block stripping mechanism and responsive to completion of movement

of said feed hopper to the position adjacent said block molding machine for effecting the reciprocation of said block stripping mechanism, a second reciprocable coupling means connecting said drive shaft to said feed hopper and actuatable in response to movement of said feed hopper to the position over said block molding machine for maintaining said block stripping mechanism against reciprocation, a vibrator mounted on said block molding machine, a second drive shaft operatively connected to said vibrator, means carried by said second coupling means and actuatable upon movement of said feed hopper to the posi-

tion over said block molding machine for operating said vibrator.
